Application November 18, 1936, Serial No. 111,470
In Canada January 20, 1936

14 Claims. (Cl. 66—8)

The invention of this case deals with hand wheel control of knitting machines, for instance multi-feed knitting machines wherein considerable effort is necessary on the part of the machine operator to turn the moving parts of the machine by hand as is necessary at certain times. Among the objects of the invention are the provision of suitable reduction gearing whereby large sized machines may be easily operated by hand, mechanism which provides adequate safety for the protection of the machine operator and a device which is automatically disengaged upon power operation of the machine thereby to prevent any damage of the machine 15 in the event of carelessness on the part of the operator.

In the drawings:

Fig. 1 is a fragmentary, plan view of as much of a multi-feed knitting machine as is necessary 20 to illustrate the application of hand wheel control thereto;

Fig. 2 is an elevation, on a relatively enlarged scale, illustrating the hand wheel drive of Fig. 1 in greater detail;

Fig. 3 is a section taken through the spindle looking to the left, Fig. 2;

Fig. 4 is a sectional view showing the worm in engagement with the ring gear of the machine;

Fig. 5 is an elevation showing a modified form 30 of the invention;

Fig. 6 is a section illustrating the manner in which the spindle as shown in Fig. 5 may be locked in an inactive position;

Fig. 7 is a section showing the manner in 35 which the worm, Fig. 5, would engage the driving gear of a knitting machine;

Fig. 8 illustrates a second modified form of the invention wherein a single hand wheel conveys motion to the driving gear of the machine 40 through a worm, worm gear and an intermediate spur gear;

Fig. 9 is a section on Fig. 8 taken through the worm gear, spur gear and interconnecting hub;

Fig. 10 is an elevation illustrating the device 45 as seen from the face of the hand wheel;

Fig. 11 is an elevation of another form of the invention showing the drive in operative position and, in the dotted lines, some parts in an inoperative position;

Fig. 12 is a detail, partly in section, showing the driving shaft in an inoperative position;

Fig. 13 is a section taken through the right hand end of the drive of Fig. 11, and showing the shaft in position for driving the machine 55 by hand; and

Fig. 14 is a detail of this same right hand end of the machine but showing parts in their inoperative position.

In multi-feed knitting machines, especially those employing a relatively great number of feeding stations, it is necessary to employ hand wheel mechanism for operating the machine manually. This hand wheel drive must provide sufficient reduction to allow the machine operator to turn the mechanism of the entire machine while exerting a reasonable amount of effort. It is also essential that the hand wheel control or controls be conveniently located and that the hand wheels themselves be of a convenient size so as not to take up too much space 15 at the side of the machine. Contrary to a more or less common practice on hosiery machines, it is absolutely necessary that the hand wheel control for these multi-feed machines be disengaged from driving connection with the 20 machine at the instant said machine is started under its own power; otherwise, as the machine was rotated under its own power it would drive the hand wheel (providing it could drive that hand wheel, which in most instances it 25 could not due to the type of gearing employed) at a rate of speed which would constitute a serious menace to the safety of anyone about the machine. For this reason the hand wheel control must be easily engageable when a machine operator desires to turn the machine by hand but must be positively and automatically disengaged the instant the machine is started under its own power. It is a further characteristic of the mechanisms herein shown that they 30 are practically incapable of being accidentally engaged during automatic operation of the machine, and even if they were, would merely be returned to inactive position in the same way in which they were returned to that position at the starting of the machine.

Referring to Figs. 1-4 a form of drive has been illustrated in which a worm is employed to engage a driving gear of the knitting machine at such times as the operator desires to turn it 45 by hand by merely rocking the hand wheel drive or drives into an engaging position, rotating the hand wheel to first take up slack and then for the purpose of turning the machine throughout such an extent as is desired, it then being a 50 function of the device itself to be moved back to initial inactive position upon automatic operation of the machine under power. The machine illustrated has a circular base 1, a rotatable needle cylinder 2 having attached thereto 55

a ring driving gear 3, herein shown as a beveled gear. It is to be understood that other types of gears are capable of being used and that it is within the scope of the invention in any one of the modifications to apply the same to any common type of gearing which may be used on the machine. Further, we illustrate each of the hand wheel drives as rotating a movable needle cylinder but in the event that such cylinder were stationary and cams movable in relation to the cylinder, the drives would of course rotate the cams and not the cylinder. On the largest machine it is found to be of advantage to provide duplicate hand wheel control at both sides of the machine and to provide each control with a hand wheel at either end. This provides an operator with four different wheels spaced about the machine so that he can normally reach one wheel while working at any position adjacent the machine and this is found to be a time saver as well as a great convenience when it is desired to watch the functioning of any particular part of the machine and at the same time to slowly turn the machine by hand. If for any reason the machine turns especially hard as is often the case with new machines just assembled, more than one person may use the hand wheel drive.

Now describing one individual drive at one side of the machine of Fig. 1, duplicate brackets 4 are suitably attached to project below the circular base 1 and are forked to provide bearings 5 at their lowermost ends within which may rock angular, forked elements indicated at 6 and provided at their forked ends with pins 7 locked by means of set screws 8. These pins 7 project into spindle bearings 9 within which a spindle 10 is free to turn. Each of the angular elements 6 has an extension 11 within which is threaded an adjusting screw 12 maintained in any adjusted position by means of locking nut 13. This adjusting screw strikes against a projection 14 cast onto one side of each of the forked brackets 4 and provides an adjustable stop to limit the swing of each element 6 in a direction to move spindle 10 and worm 15 from driving position. The worm 15 is fixed to spindle 10 at about its mid-point by means of a taper pin or by any other suitable retaining means and said spindle is further maintained in proper relative position by means of collars 16 which, of course, may be adjusted along the length of the spindle for the purpose of positioning parts in exact working relationship. A ball thrust bearing 16' is interposed between bearing 9 and collar 16 at one end of the spindle. At least one of the forked ends of one of the elements 6 is provided with an adjusting screw 17 maintained by a locking nut 18 which screw bears against a lug 19. This adjusting screw stops the movement of elements 6, the spindle 10 and worm 15 when the worm has been rocked into complete engagement with ring gear 3 and serves to take the thrust as the hand wheel drive is used to rotate the machine. A hand wheel 20 having a grip 21 is fixed at each end of spindle 10.

It is obvious that only one of the extensions 11 need be provided with an adjustable stop screw and that only one stop screw 17 would suffice to permit satisfactory operation of the drive, but in the preferred embodiment of the invention we employ two of these stopping screws 17 within one of the forked ends of both elements 6 and a screw 12 in both extensions 11. A guard 22 has been provided which covers a part of ring

gear 3 and worm 15 at the position illustrated but is not an essential element except for purposes of safety and appearance.

We have illustrated in Fig. 2 a full line position of all elements wherein the drive is shown in active position. Certain fragments of the spindle worm, collars and bearings have been shown in dotted line position to illustrate the manner in which the worm is rocked away from engagement with gear 3 as soon as the machine is started under its own power. It is obvious that the single threaded worm gives the machine operator a sufficient mechanical advantage whereby he may rotate the machine by hand with a minimum of effort. It is obviously impossible for gear 3 to rotate the worm. It is only by pushing spindle 10 and the rest of the mechanism to the left, Fig. 2, until the worm engages the teeth of gear 3, and by turning the hand wheel until stopping screws 17 strike abutments 19, that the mechanism becomes effective to rotate the machine. These parts are only maintained in that position as long as the operator continues to turn the hand wheel in a direction to rotate the machine or until the machine is started; the instant the machine is started, ring gear 3 will merely move worm 15, spindle 10, etc., back to the dotted line or inactive position. The hand wheel will not be turned by the machine during this disengaging movement and in the event one should attempt to engage the hand wheel drive during automatic operation of the machine, teeth of gear 3 would merely return the drive to the inactive position in which said drive would normally remain under the influence of gravity.

Now referring to Figs. 5, 6 and 7, a modification of the invention has been illustrated in which a spindle 23 having a worm 24 fixed thereto is both slidable and capable of rotating in bearings 25 formed as a part of brackets 26 suitably secured to the lower edge of the circular base 1. This spindle 23 may have a hand wheel at one end or preferably at both ends similar to the construction shown in Figs. 1-4. The worm 24 engages a bevel gear 27 attached to the rotating part of the knitting machine, which gear may be of the type shown in Fig. 4 or might be a spur or any other gear suitable for the purpose; the principle of the invention would not be altered thereby. A collar 28 is fixed by means of set screw 29 to the spindle and maintains a ball thrust bearing 30 in position to engage against one end of the bearing 25 at the right, Fig. 5, when the hand wheel assembly is pushed to the operative position shown in full lines in that view. To turn the machine by means of the hand wheel it is only necessary for the operator to push the spindle, worm and hand wheel or wheels to the left, Fig. 5, until the worm engages the teeth of gear 27 and then to turn the wheel until thrust bearing 30 engages against the bearing 25. Further turning of the hand wheel will cause the needle cylinder or other rotating element of the knitting machine to advance in a forward direction. When the machine is started under its own power this hand wheel assembly will be moved to the dot and dash line position of Fig. 5, this movement being in a direction tangential to the pitch circle of the ring gear and depending upon the size of the ring gear, will have to be enough to assure that the worm 24 moves safely beyond a position where it would engage any of the teeth of the gear.

When moved to inoperative position the assembly will be held in that position against any

inadvertent movement by means of a latch 31 engaging a groove 32 in the spindle. This latch 31 is pivoted at 33 and is held downwardly against the spindle by means of a spring 34 attached at 5 one end to the latch and at the other end to a pin 35 as shown. A collar 36 attached to the end of the left hand bearing 25, Fig. 5, has a slot 37 within which the latch 31 works. This slotted collar assists the screw 33 and latch 31 in over- 10 coming the thrust of the spindle and attached parts when any attempt is made to push it into operative position without first lifting the latch; thus said latch functions as a safety device against inadvertent use of the worm 24 and ring gear 27. 15 As the assembly is moved to inactive position latch 31 will snap into the groove and prevent the spindle and attached parts from moving too far in that direction. A guard 38 is attached to the base 1 and encloses the worm and part 20 of the spindle.

Referring to Figs. 8, 9 and 10 another form of the invention has been illustrated wherein a hand wheel works through a worm and worm gear to rotate an intermediate gear or pinion which 25 engages the ring gear for rotating the machine. To the circular base 1 we have attached by suitable connecting means a plate 39 which has a boss or hub 40 projecting downwardly therefrom. The spindle 41 having a head 42 is inserted within 30 this boss and is held from rotating therein by means of a pin 43. The said spindle serves as a bearing upon which bracket 44 having two arms 45 and 46 is free to swing. Hand wheel 47 having a grip 48 is fixed to a short shaft 49 which 35 projects through a bearing in bracket 44 and has a worm 50 keyed or otherwise attached in such a way it will not rotate thereon at the other end of the spindle. A pin 51 passes through the ends of arms 45 and 46 to provide a bearing upon which 40 a hub 52 may rotate, this hub having formed integral therewith a worm gear 53 and a pinion 54. A spring 55 is attached to a pin 56 on one arm of the bracket and to any projecting element such as a pin 57 attached to plate 39 so 45 that said bracket and the forked arms with the attached hand wheel, worm, worm gear and pinion will normally be moved to such a position that pinion 54 will not engage a ring gear 58 which rotates the cylinder or other rotating element of the machine.

Whenever the operator desires to turn the machine by hand, it is only necessary for him to grip the hand wheel and swing it from the dot and dash line position of Fig. 8 to such a position 55 that the teeth of the pinion engage those of the ring gear, then to turn the hand wheel until said teeth have become fully engaged whereupon the recessed end 59 of arm 46 strikes against the edge of base 1. This recess 59 may be ground 60 off in such a way that proper intermeshing of the pinion and gear will be realized. Whenever the machine is started under its own power pinion 54 and the entire swinging hand wheel assembly will be moved to inoperative position and will 65 be held in that position by means of the spring 55. A casing or guard 60 enclosing all parts except the hand wheel has been attached to plate 39 and is provided with a slot 61 through which spindle 49 projects, this slot being of sufficient size to allow the swinging of the wheel from 70 operative to inoperative position and vice versa.

Now referring to Figs. 11-14, we will describe another form of the invention wherein the drive is disengaged by sliding of the shaft and worm, 75 and, at the same time, accompanying this sliding

movement by lowering one end of the shaft. The base 1, driving gear 3 for rotating the cylinder and a guard 22 correspond to equivalent parts in the first two forms of the invention described. A shaft or spindle 62 has fixed thereon a worm 5 63 which may be meshed with gear 3 and upon rotation of the shaft and worm by a suitable crank or hand wheel, will drive gear 3 and other parts of the machine. This shaft 62 is rotatably guided at one end within a bearing 64 formed 10 in extension of a bracket 65 which is in turn permanently fixed to the circular base of the machine 1. This shaft carries collars 66 and 67 both adjustably secured along the length of the shaft by suitable set screws or other attaching 15 means. A thrust bearing 68 is provided between collar 66 and the bearing 64 and serves the same purpose as bearing 30, Fig. 5. This shaft 62 must be capable of sliding and rocking to a limited extent within the bearing 64, and for this 20 reason, that bearing will be formed with a certain amount of play for rocking the shaft as shown in Figs. 11 and 12.

Now referring to the right hand end of Fig. 11 and to Figs. 13 and 14, a bracket generally indicated by numeral 69 is attached to the underside of the circular base. This bracket is constructed in such a manner that it presents a depending forked portion 70 and 71 at either side of the shaft and a web 72, these forked ends 70 and 71 and the web 72 preventing movement sidewise and also restricting the upward movement of the shaft as shown. The said shaft has an elongated collar 73 attached in the position shown in Figs. 11, 13 and 14 and which bears within 25 the bracket, this collar also serving as an abutment to throw the shaft and worm into active position, but will allow the same to rock or swing 30 downwardly upon starting of the machine under power.

Each of these arms 70, 71 is cored out to provide an opening 74 and a slot at the bottom of that opening within which is pivoted means for raising the spindle 62 to level position and which will allow it to drop to the dotted line position 45 of Fig. 11 when desired. This mechanism consists of a rectangular block 75, projections at either side thereof for engagement within the bearing slots, a crank arm 76 and small handle 77. In the position of Figs. 11 and 13, the crank 50 has been turned to upper position whereupon the rectangular block 75 has raised the spindle, and thru collar 73, has pushed the same to the left, Fig. 11 to engage the worm with the gear. As the spindle is raised and tends to slide to the left, it will be necessary to turn the hand wheel slightly to mesh the worm and gear until thrust bearing 68 moves up against the stationary bearing 64. In that position the hand wheel may be used to rotate the machine as long as desired. 60

When the machine is again started under power, the gear 3 still meshing with the worm will cause it and shaft 62 to move to the right whereupon element 75 will be tripped to allow the right hand end of the shaft to follow as shown 65 in dotted lines, Fig. 11, and further in Fig. 14. From an inspection of Figs. 11-14 it can be seen that the center about which crank 76 turns is offset with respect to the center line of the rectangular block 75.

This prevents the weight of shaft 62, worm 63 etc. accidentally tripping the block and disengaging the driving mechanism. This particular form of the invention comprises the advantages of forms numbered 1 and 2 but provides a very 75

simple way for rocking one end of the shaft downwardly and at the same time, sliding that shaft along its length until the driving worm has moved to a position in which it can not engage the gear 3. The reverse movement is likewise effected with a minimum of effort. The mechanism itself is much simpler and more easily manufactured than that of either of the other forms. It is to be understood that any one of the 10 modifications of hand operating mechanism may be used singly on a multi-feed or other knitting machine or that several may be used on the same machine. The hand operating mechanism may be used on multi-feed machines or on any other 15 knitting or textile machines wherein it is desirable to manipulate the machine by hand and to have positive actuating mechanism which will be automatically disengaged but which can not be accidentally moved to active position to cause 20 any damage to the machine or to injure any employee who is working on the machine. The invention has been described in more or less specific terms for purposes of illustration only, and we are not to be limited except by the scope of 25 the attached claims.

We claim:

1. In a knitting machine of the type described, a driven element and a ring gear for driving the same, manually operated driving means including a worm engageable for driving said driven element through the gear, said worm being automatically disengaged upon power operation of the machine.

2. In a knitting machine a driven element, a 35 ring gear for driving said element, and driving means for engaging said ring gear including gearing capable of driving said ring gear but incapable of being driven by the ring gear, said gearing being engageable with the ring gear at will and automatically desengaged therefrom when the machine is started under power.

3. In a knitting machine the combination of a driven element and a ring gear for driving the same, manually operated driving means for the 45 ring gear including a shaft, a hand wheel and bearings for said shaft, means driven from said shaft to engage and drive the ring gear, said means being manually engageable with the ring gear, but positively disengaged from the ring gear upon power operation of the machine.

4. In a knitting machine the combination of a driven element and a ring gear attached thereto, manually operated means for driving said ring gear so constructed and operated that it may be 55 engaged with the ring gear at will but will automatically disengage upon power operation of the machine and will remain in disengaged position throughout the period of power operation.

5. A knitting machine having in combination 60 a driven element and a ring gear attached thereto, means for manually driving the ring gear and element including a shaft, means thereon for engaging the driving and ring gear, bearings for said shaft being pivotally mounted in a pair of 65 swinging elements, said swinging elements being capable of maintaining the shaft and driving means in a position to engage and drive the ring gear but being movable upon power operation of the machine to a position wherein the ring gear 70 will not be engaged by the driving means.

6. In a knitting machine of the type described, the combination of a driven element and a ring gear attached thereto for driving the same, a pair of brackets attached to said machine, swinging 75 members pivoting on the bracket and stop-

ping means to limit movement of the swinging members in both directions, bearings on the swinging members and a shaft rotatable in said bearings, a hand wheel fixed to the shaft and a worm on the shaft for engaging the ring gear, whereby said hand wheel, shaft and worm may be rocked into a position to drive the ring gear and driven element and may be moved to inactive position upon power operation of the machine.

7. In a knitting machine the combination of a driving element and a ring gear attached thereto, bearings attached to the machine and a shaft rotatable and slideable within said bearings, a hand wheel on said shaft and driving means fixed thereto, means on the shaft for limiting sliding movement in one direction in which position the driving means on the shaft will engage the ring gear before mentioned whereby the machine may be manually operated, but upon power operation of said shaft, driving means and hand wheel will be moved axially of the bearings until said driving means disengages from the hand wheel.

8. A knitting machine having in combination a driven element and a ring gear attached thereto, bearings attached to the machine and a shaft arranged to slide and to rotate in said bearings, a hand wheel on said shaft and a worm fixed thereon for engagement with said ring gear, a 30 collar on the shaft for limiting its movement in one direction and safety means functioning to limit movement of the shaft in the other direction and also to prevent its return except at the will of the machine operator.

9. A knitting machine having in combination a driven element and a ring gear attached thereto, bearings attached to the machine and a shaft arranged to slide and to rotate in said bearings, a hand wheel on said shaft and a worm fixed 40 thereon for engagement with the ring gear, a collar on the shaft for limiting its movement in one direction and safety means functioning upon said shaft including a groove for preventing the return of said shaft and driving means into engagement with the ring gear except upon release of the latch by the machine operator.

10. In a knitting machine the combination of a driving element and a ring gear attached thereto, hand operated means for driving the element through the ring gear at desired intervals including a shaft and a worm thereon, said shaft and worm being movable tangentially of the gear to and from active position and means for limiting the movement of said shaft and worm in either direction.

11. In a knitting machine, the combination of a driven element and a ring gear for driving the same, manually operated driving means for the ring gear including a shaft, a hand wheel and bearings for said shaft, a worm on said shaft engageable with said ring gear, the construction being such that said shaft is slideable within its bearings and also capable of being rocked about one of the bearings as a pivot thereby to disengage the worm from the ring gear.

12. In a knitting machine, a driven element and a ring gear for driving the same, manually operated driving means for said ring gear including a shaft, a worm, a hand wheel for turning said shaft and bearings within which said shaft may turn, one of said bearings providing for the sliding of said shaft lengthwise thereof, and the other of said bearings comprising means for restraining the shaft in a position wherein the worm may 70 75

engage the gear but allowing that end of the shaft to be lowered, the combined sliding and lowering of the shaft resulting in disengagement of the worm from the gear.

- 5 13. In a knitting machine, a driven element and a ring gear for driving the same, manually operated driving means for said ring gear including a shaft, a hand wheel, a worm on the shaft for engagement with the ring gear, bearing means within which the shaft may rotate, said bearing means being constructed to allow a combined sliding and rocking movement to be imparted to said shaft thereby to disengage the worm from the gear.
- 10 14. In a knitting machine, a driven element for

driving the same, manually operated means for driving said ring gear including a shaft, a worm fixed to said shaft for engagement with the gear, a hand wheel for rotating the shaft, a bearing at one end of said shaft within which it may rotate, 5 collars on said shaft to allow sliding movement of the shaft within the bearing, but to limit the extent of said sliding movement, bearing means for said shaft at the opposite end including means for restraining the shaft laterally and other 10 means for raising and lowering that end of the shaft and locking it in raised position.

ROBERT H. LAWSON.
WILLIAM L. SMITH, JR. 15
